UNITED STATES PATENT OFFICE.

ALFRED CLEMENT COTY AND THOMAS EARL COTY, OF WATERTOWN, NEW YORK.

BAG-FEEDING MACHINE.

Application filed December 30, 1926. Serial No. 157,955.

This invention is an improvement in bag feeding machines, and more particularly in machines for feeding bag blanks of tubular shape.

5 Bags of this character are made by turning over the edges of a web or suitable material onto each other, and securing them together, as for instance by paste, to form a continuous tube. The tube is afterwards 10 cut into suitable lengths, each designed for a single bag.

Usually the bags carry display advertising in the form of printed matter, and one end and sometimes both ends of the tube are 15 closed, by forming folds in the said end or ends, the folds being secured together. Thus two or three separate handlings of the bag blanks are required, that is the blanks must be fed two or three times, and in each feeding 20 exact alinement is desirable.

In feeding to the mechanism for folding the end or ends of the blank, it is essential that the tube be opened to facilitate the formation of the folds, and to enable this 25 operation to be more easily performed and to facilitate the handling of the bag in the folding of the end or ends, the blanks are provided at one end and on one wall with a tab, the other end of the wall having a 30 thumb cut, provided by the formation of the tab in a succeeding blank.

It is obvious that the feeding, whether for printing or end folding requires a high degree of accuracy. The bag blanks must be 35 correctly alined, and with the folding machine each must be delivered in exact relation to the bottomer or mechanism which folds the end. Otherwise uniform bags can not result.

40 One of the primary objects of the present invention is the provision of a machine having mechanism for feeding the blanks, adapted to feed in any of the operations above mentioned in an accurate manner, and 45 with each blank positioned when delivered to the operating machine in precisely the same position as the preceding blank.

Another object is the provision of a simple, inexpensive and easily operated machine, wherein all the several operations are 50 carried out automatically.

With these and other objects in view the invention consists in the construction and novel combination of parts fully described 55 hereinafter, illustrated in the accompanying drawings, and pointed out in the claims ap-

pended hereto, it being understood that various changes in the form, proportion, size and minor details of construction within the scope of the claims, may be resorted to without departing from the spirit of the invention. 60

In the drawings forming a part hereof:—

Fig. 1 is a side elevation of the improved machine. 65

Fig. 2 is a top plan view with parts broken away.

Fig. 3 is an end view looking toward the left of Fig. 1.

Fig. 4 is a detail sectional view at the 70 lower end of the magazine, showing the manner of opening the tubular blank.

Fig. 5 is a plan view of one end of Fig. 4.

Fig. 6 is a detail of the movable blank end supporting mechanism with the parts in 75 one position.

Fig. 7 is a detail in side elevation showing the pressing fingers and the blank withdrawing mechanism.

Fig. 8 is a detail in side elevation of the 80 blank alining mechanism.

Fig. 9 is a section on the line 9—9 of Fig. 8.

Figure 10 is an enlarged detail showing more clearly the relation of the resilient 85 strips 12 and the opener blade 44 hereinafter described.

The bag blanks 1 as previously mentioned, usually have at one end a tab 2, and at the other end a thumb cut or notch 3, the 90 said tab and thumb cut being in one wall of the blank, and the thumb cut of each blank resulting from the formation of the tab in a preceding blank. These elements, namely the tab and thumb cut are desirable in 95 the folding of the bag ends, as they provide means for positively holding one side wall of the blank by the tab, and for enabling the piercing and holding of the other wall by means of pins or the like. The tab also 100 facilitates the separation of the blanks, and the thumb cut the separation of the walls of the blanks.

In the present embodiment of the invention, a number of the tubular blanks in similar superimposed relation are placed in a magazine, composed of a bottom 4, at least one side wall 5, and stops 6 at one end, against which the ends of the blanks abut. The magazine as shown in Fig. 1 inclines 110 downwardly toward the stops 6, and the blanks are arranged with the wall having

the tab and thumb cut upward, and with the tabs at the forward ends, that is adjacent the stops 6.

The stops 6 are carried by a rod 7 arranged transversely of a suitable supporting frame 8 for the machine, and held in bearings 9 in the frame. The stops are arranged in spaced relation as shown in Fig. 3, each near one side of the magazine, and each stop has a split bearing 10 engaging the rod 7, and secured thereon by a set screw 11. The stops 6 as shown more particularly in Fig. 3, extend well below the rod 7, and below the bottom of the magazine, and each has secured to the lower end thereof of a strip 12 of flexible material for a purpose to be presently described.

Referring to Fig. 1, it will be noticed that the bottom 4 extends only a little beyond the median line of the blanks when in the magazine, so that a little more than one third of the lowermost blank is unsupported by the bottom at the end adjacent the stops. At each of the forward corners, the pile of blanks is supported by an angle plate 13 secured to a rod 14 adjustably held on a shaft 15 mounted at the appropriate side of the magazine and extending parallel with the long axes of the blanks. A bearing block 16 connects each rod to the shaft, the block having split bearings for engaging the rod and the shaft respectively, thereby to adjustably connect the block to both rod and shaft.

Each shaft 15 is held in a sleeve bearing 17 on the frame, and each shaft carries a roller 18 engaging a cam plate 19 secured to a vertical shaft 20 journaled in the frame, and operated in a manner to be presently described. The arrangement of the cam is such that when the shaft 20 is oscillated in one direction, the plates 13 are swung downwardly and outwardly into inoperative or nonsupporting position, while when the shaft is oscillated in the opposite direction the plates are swung upwardly and inwardly into operative or supporting position.

The shaft is oscillated by means of a cam 21 on a shaft 22 journaled transversely of the frame, the shaft 20 having an eccentrically carried roller 23 engaging a face groove in the cam. As shown, the roller 23 is adjustably connected to the shaft 20 by means of a split bearing 24. A coil spring 25 normally acts on the shaft 15 to swing the plates 13 into inoperative position, and to hold the roller 18 in close engagement with the cam 19.

Each cam 19 carries a separating and supporting finger 26 (Figure 5). The cam has a depending bearing 27 in which the finger 26 is held, and it will be noticed referring to Fig. 5 that the finger is roughly T shaped, the shank of the T engaging the bearing 27.

One end 28 of the cross arm of the T, name-

ly that end adjacent the bags is short and conical, to readily enter between the lowermost bag and those above, while the other end 29 of the cross arm is of considerable length, to provide an efficient support for the superincumbent bags, when the finger is in operative position. As shown in Figures 4 and 5, the shank of the finger is adjustably held by the cam.

Between the plates 13 the forward ends of the bags are supported at the center at certain intervals by means of a plate or blade 30. The blade is secured to a bracket 35 having a split bearing engaging a shaft 33, and clamped thereon as shown. The blade has an oscillating movement imparted thereto by the mechanism shown in Fig. 1. This mechanism includes a gear segment 38 journaled at 39 on the frame, and engaging a mutilated pinion 40 on the shaft 33. The segment 38 carries a friction roller 41, engaging within a face groove in a cam wheel 42 secured to a shaft 43, journaled transversely of the frame.

The cam groove is so contoured that once during each complete rotation of the shaft 43 the segment will be rocked to oscillate the shaft 33. When the shaft is oscillated in one direction, the plate is swung upwardly into engagement with the tab of the lowermost bag blank, and supports the upper wall of said blank and the blanks above, leaving the lower wall free so that the opener blade to be described can easily enter between the walls.

Resilient fingers 30^a are provided for forcing several of the tubular blanks down upon the blade 30 at each side thereof. That is these fingers engage between one or more of the lower blanks and those above, on each side of the blade 30 and make downward pressure, thus to bow transversely the forward ends of the lower blank or blanks. Since the lower wall of the lowermost blank is free, it moves away from the upper wall and blade 30, forming a pocket into which the opener blade to be described may enter.

The fingers 30^a are adjustably held in split bearings 34 by set screws 36. The bearings are clamped on a short shaft 31, held in the bracket 32. This shaft has a radial arm 37 provided with an angular cam slot, engaged by a roller 38 on a fixed arm 39 depending from the rod 7. The fingers 30^a are of laminated structure, and are resilient, built up like a cantilever spring. When the shaft 33 is oscillated as above described, the fingers 30^a are first moved between several of the lowermost blanks and those above, and afterwards downwardly, thus to bow the blank over the blade 30 and to provide the pocket between the lower tubular blank walls as above described.

While the forward end of the lowermost blank is manipulated as just described, an

opener blade 44 is inserted between the walls of the tubular blank. The blade 44 is carried by a substantially S shaped arm 45, pivoted at 46 to a collar 47 secured on the shaft 43 before mentioned. That end of the arm remote from the blade has a friction roller 48, engaging a face groove in a cam 49 journaled on the shaft 43, and held stationary by an arm 50 secured to a shaft 51, journaled in the frame, parallel with the shaft 43 and below and behind the same.

The outer wall of the cam groove is lacking over about 90°, so that at a selected point in the rotation of the cam the roller is free to move away from the shaft 43. A coil spring 53 is arranged between the arm and the collar 47, the spring acting to hold the roller in engagement with the inner wall of the groove. The cam is adjustably connected with the arm 50 by the slot and set screw 52 shown in Fig. 1.

The blade 44 is resilient and may deflect under pressure to prevent injury to the upper wall of the bag blank as it moves between the walls. The cam 49 allows the arm to swing downwardly from the position of Fig. 1 under excess pressure thus to prevent injury to the parts, and the spring returns the arm to normal position as soon as the pressure relaxes.

As the blade 44 moves into the blank between the walls thereof, the end of the blank is opened, the lower wall being drawn away from the upper wall which is supported by the blade 30. In order to limit the opening movement and to prevent kinking and bending of the blank, as well as to reduce friction, a roller 54 is arranged transversely of the machine just below the magazine, and just in front of the forward end of the bottom 4. As the forward end of the blank is drawn down in the manner shown in Fig. 6, the plates 13 are lowered and the blank is drawn down onto the roller 54.

The fingers 26 are moved into position between the lowermost blank and those above when the plates 13 are lowered, and the uppermost blanks are supported clear of the lowermost. A pair of segments 55 is secured to the shaft 43, and the segments are arranged in rear of the arm 45, to engage above the lowermost blank as it is bent around the roller 54. As the segments move onward, the periphery of the curved surfaces thereof cooperate with the roller 54 as feed rollers to move the blank rearwardly and to deliver it to a pair of rollers 56 and 57 journaled on shafts 58 and 59 in the frame.

In order to attain accurate delivery the blanks are alined laterally and longitudinally. The lateral alinement is attained by U shaped guides 60 adjustably secured to rods 61 extending inwardly from the sides of the frame. The guides are adjustable on the rods toward and from each other, and the

side edges of the blanks move in the guides. Longitudinal adjustment is attained by a pair of arms 62 secured to a shaft 63 journaled in one end of the cross-head 64 on the shaft 58. A spring 65 is arranged between an arm 66 on the shaft and the cross-head, the said spring acting to hold a friction roller 67 on the shaft 36 against a cam 68 on the shaft 58.

The roller 67 is on a radial extending arm 69, and the cam is contoured to swing the free ends of the arms toward the segments 55 just before the arms attain the position of Fig. 8. The free ends of the arms are grooved transversely as shown at 69 on the faces adjacent to the segments, the bottoms of the grooves being in alinement with the contacting surfaces of the rollers 56 and 57. These arms engage the forward end of the blank, and move it slightly if necessary, to attain longitudinal alinement. From the rollers 56 and 57 the forms are delivered to the rolls 70—71, of the machine which performs the next operation.

During the passage of the blanks from between the roller 54 and the segments 55, they are supported by a table or plate 72. This plate is supported at its front end by an arm 73 secured to the fixed shaft 51 before mentioned and at its rear end by a standard 74 on the frame. The improved feeding machine may be driven in any suitable manner, as for instance by the machine to which it delivers. In this manner the operation thereof may be easily synchronized with the operation of the said machine.

The shaft of the roller 70 carries a gear 75 connected by idlers 76 and 77 with a gear 78 on the shaft 22. Through an idler 79 on the fixed shaft 51 the gear 78 is connected with a gear 80 on the shaft 43. The wheel 56 is driven by the wheel 57, and the roller 54 is preferably composed of several sections, as shown in Fig. 3. In order to thoroughly loosen the lowermost bag blank, break up air adhesions between it and the next above, a roller 81 is journaled in open bearings 82 just behind the roller 54. This roller 81 has portions thereof hexagonal as shown in Fig. 2.

To prevent the points of the segments 55 from engaging the tubular blanks at the end of the pile, the strips 12 of flexible material previously mentioned are secured to the lower ends of the stops 6 in register with the segments. When the segments swing into the position of Fig. 7, the flexible strips are swept in beneath the pile of the blanks as shown in Fig. 7, thus preventing any interference with the ends of the blanks in the pile.

The operation of the machine is as follows. A pile of similarly arranged tubular blanks is placed in the magazine, with the front ends abutting the stops 6, and the side

- edges at one side abutting the guide plate 5. At this time the plates 13 are in the position of Figures 1 and 7, and the fingers 26 are in the position of Figure 7, that is both beneath the lowermost blank of the pile. The arrangement of the magazine is such that while the bottom 4 supports the pile at one end, the other end is supported by the plates 13 and the fingers 26.
- 10 When the shaft 22 commences to rotate, the parts attain the position of Fig. 1, with the blade 30 engaging beneath the tab of the lowermost blank. The fingers 30^a, Figure 2, come into engaging position between the lowermost blank, or between several of the lowermost blanks and those above and are operated to press down upon the blank or blanks, thus to separate the walls of the lowermost blank, since the lower wall is at this time unsupported between the plates 13. The blade 44 now enters the pocket, moving between the walls of the blank, and bending down the blank in the manner shown in Figure 6. As the blade enters the blank, the plates 13 are moved into the inoperative position of Figure 4, as are also the fingers 26.

The blade 30 is meanwhile passing on to the position of Figure 7, and the plates 13 and the fingers 26 are returned to the operative position of Figure 7. Soon thereafter the blade 44 passes out of engagement with the blank, as shown in Figure 7, and the segments 47 engage the blank and cooperating with the roller 54 feed it to the rollers 56 and 57. The resilient strips 12 have been swept in beneath the end of the pile by the segment points, thus insuring that the said points will clear the pile of blanks. During its passage from the segments and roller 54 to the rollers 70 and 71, the blank is supported by the table 72, and in its travel it is alined laterally between guide 60, and longitudinally by the fingers 62, so that it enters between the rollers 70 and 71 accurately positioned for operation by the machine of which the said rollers form a part. After the blank is withdrawn over the rollers 54 and 81, the latter roller thoroughly breaks up air adhesions and the like between the lowermost blank and those above, so that there is no tendency to carry along another blank.

The roller 54 is resiliently mounted, and spring pressed toward the segments. At its ends it is journaled in bearing blocks 85, which are slidable in guides 90 on the frame. A coil spring 91 is arranged in rear of each block, and the block and spring are engaged by tension screws 92 and 93 respectively threaded through the frame. By means of the screws, the position of the roller with respect to the segments, and the tension of the spring may be adjusted. The machine is adjustable for bag blanks of different sizes.

The stops 6 may be adjusted toward and from each other for bags of different widths, as may also the guides 60. The plates 13 are adjustable toward and from each other, and the fingers 26 are also adjustable with respect to the cams 19.

While the bag blank is passing over the table 72, between the rollers 56 and 57, Figure 8, it is engaged along its central portion, and is easily swung laterally at either end. As the front end passes from between the rollers 56 and 57 it engages the lateral guides 60, Figs. 1 and 9, and if out of alinement the front end will be swung, the remainder of the blank will follow, and the blank will be fed in exact lateral alinement to the rollers 70—71. The guides 60 flare somewhat at the entrance end to facilitate the entrance of the blank.

What is claimed as new is:

1. In a machine of the class described, a magazine constructed to support a pile of tubular bag blanks in superposed relation with the underside of one end of the lowermost blank free, a blade to engage and support the upper wall of the lowermost blank near the center of the said end, and means to press said wall downwardly at each side of the blade, thereby to form a pocket to facilitate the entrance of opening means. 95

2. In a machine of the class described, a magazine constructed to support a pile of tubular bag blanks in superposed relation with the underside of one end of the lowermost blank free, a blade to engage and support the upper wall of the lowermost blank near the center of the said end, means to press said wall downwardly at each side of the blade, thereby to form a pocket to facilitate the entrance of opening means, and means entering the pocket for opening the end of the blank and bending said end downwardly. 105

3. In a machine of the class described, a magazine constructed to support a pile of tubular bag blanks in superposed relation with the underside of one end of the lowermost blank free, a blade to engage and support the upper wall of the lowermost blank near the center of the said end, means to press said wall downwardly at each side of the blade, thereby to form a pocket to facilitate the entrance of opening means, means entering the pocket for opening the end of the blank and bending said end downwardly, and mechanism for engaging the said end and withdrawing the blank from the magazine. 115

4. In a machine of the class described, a magazine constructed to support a pile of tubular bag blanks in superposed relation with the underside of one end of the lowermost blank free, a blade to engage and support the upper wall of the lowermost blank near the center of the said end, fingers 125

to press said wall downwardly at each side of the blade, thereby to form a pocket to facilitate the entrance of opening means, means entering the pocket for opening the end of the blank and bending said end downwardly, and mechanism including a resiliently supported roller over which the blank is drawn for engaging the said end and withdrawing the blank from the magazine.

5. In a machine of the class described, a magazine constructed to support a pile of tubular bag blanks in superposed relation with the underside of one end of the lowermost blank free, a plurality of means cooperating to separate the walls of the lowermost blank at the said end and to temporarily support the upper wall, an opener blade mounted to move into the said opened end and bend the end of the blank downwardly, means engaging the said end to withdraw the blank, and mechanism in connection with the magazine movable into and out of operative position for engaging beneath the pile at the said end and synchronized with the operation of the bending and withdrawing means to move into inoperative position during the operation of the bending means and into operative position during the operation of the withdrawing means.

6. In a machine of the class described, a magazine constructed to support a pile of tubular bag blanks in superposed relation with the underside of one end of the lowermost blank free, a plurality of means cooperating to separate the walls of the lowermost blank at the said end and to temporarily support the upper wall, an opener blade mounted to move into the said opened end and bend the end of the blank downwardly, means engaging the said end to withdraw the blank, mechanism in connection with the magazine movable into and out of operative position for engaging beneath the pile at the said end and synchronized with the operation of the bending and withdrawing means to move into inoperative position during the operation of the bending means and into operative position during the operation of the withdrawing means, and guides engaging the edges of the blank to aline the same as it moves away from the magazine.

7. In a machine of the class described, a magazine for a pile of tubular bag blanks, a pair of feed rollers, a plurality of means cooperating to withdraw the lowermost blank from the pile and deliver it to the feed rollers, and means moving in the opposite direction to the travel of the blank to engage the front end thereof prior to its engagement by the feed rollers to determine the position thereof with respect to said rollers.

8. In a machine of the class described, a

magazine having means to support one end of a pile of tubular bag blanks in superposed relation, a blade at the other end of the magazine movable into and out of position to support the upper wall of the lowermost blank near the center of the said end, fingers to engage said wall and press it downwardly at each side of the blade thereby to form a pocket, an opener to enter the pocket and to bend the end of the blank downwardly, means engaging the said end to withdraw the blank, and means movable into and out of supporting position to engage the said other end of the pile during the operation of the withdrawing means.

9. In a machine of the class described, a magazine having means to support one end of a pile of tubular bag blanks in superposed relation, a blade at the other end of the magazine movable into and out of position to support the upper wall of the lowermost blank near the center of the said end, fingers to engage said wall and press it downwardly at each side of the blade thereby to form a pocket, an opener to enter the pocket and to bend the end of the blank downwardly, means engaging the said end to withdraw the blank, and means movable into and out of supporting position to engage the said other end of the pile during the operation of the withdrawing means, the withdrawing means including a resiliently supported roller over which the blank is drawn.

10. In a machine of the class described, a magazine having means to support one end of a pile of tubular bag blanks in superposed relation, a blade at the other end of the magazine movable into and out of position to support the upper wall of the lowermost blank near the center of the said end, fingers to engage said wall and press it downwardly at each side of the blade thereby to form a pocket, an opener to enter the pocket and to bend the end of the blank downwardly, means engaging the said end to withdraw the blank, and means movable into and out of supporting position to engage the said other end of the pile during the operation of the withdrawing means, the withdrawing means including a resiliently supported roller over which the blank is drawn, and wheel segments cooperating with the roller to engage the edges of the blank.

11. In a machine of the class described, a magazine having means to support one end of a pile of tubular bag blanks in superposed relation, a blade at the other end of the magazine movable into and out of position to support the upper wall of the lowermost blank near the center of the said end, fingers to engage said wall and press it downwardly at each side of the blade thereby to form a pocket, an opener to enter the pocket and to bend the end of the blank downwardly,

- means engaging the said end to withdraw the blank, and means movable into and out of supporting position to engage the said other end of the pile during the operation of 5 the withdrawing means, the withdrawing means including a resiliently supported roller over which the blank is drawn, and wheel segments cooperating with the roller to engage the edges of the blank, the magazine 10 having flexible strips at the corners thereof depending below the blanks and positioned to be engaged by the segments for the purpose specified.
12. In a machine of the class described, a 15 magazine including means to support one end of a pile of superposed bag blanks, and means movable into and out of operative position to support the pile at the other end, a plurality of mechanisms at the said other 20 end to withdraw the lowermost blank from the pile, and means for operating the said means and the said mechanisms to cause the supporting means to release the lowermost blank during the early part of the withdrawal 25 operation and to engage and support the remaining blanks during the later part of the operation, the withdrawing mechanism including an opener blade to pull down the unsupported end of the lowermost blank, and a resiliently supported roller and wheel segments cooperating therewith to withdraw the blank.
13. In a machine for successively feeding from a pile the lowermost of a plurality of 30 superposed similarly arranged tubular bag blanks each provided at one end with a tab on the upper wall thereof, a magazine including a fixed support for one end of the pile and a movable support for the other end, 35 said movable support arranged to engage the pile on each side of the tab, a blade for engaging beneath the tab of the lowermost bag blank, fingers to engage above the blank on opposite sides of the blade and to press the blank downwardly, an opener to enter the 40 blank between the walls thereof and to bend down the end, mechanism to engage the said end to withdraw the blank, and means to operate the blade, the fingers, the movable support, the opener and the withdrawing 45 means in proper order and relation.
14. In a machine for successively feeding from the bottom of a pile of similarly arranged tubular bag blanks each having the upper wall at one end extended, a blade for 50 engaging the extension of the lowermost blank, fingers to depress the blank on each side of the blade, an opener blade to enter between the walls and bend down the end of the blank, other means to engage said end 55 and withdraw the blank, and means to operate all of said mechanisms in the proper order.
15. In a machine of the class described, a 60 magazine for holding a pile of tubular bag blanks, a pair of feed rollers, a plurality of means cooperating to withdraw the lowermost blank in the pile and deliver it to the feed rollers, and a plurality of means cooperating to determine the position of the 65 blank with respect to the feed rollers, said means engaging the end and sides respectively of the blank.

Signed at Watertown, in the county of Jefferson and State of New York, this 12th 70 day of August, A. D. 1926.

ALFRED CLEMENT COTY.
THOMAS EARL COTY.
